Primary Examiner—Robert M. Spear*Assistant Examiner*—Karen Acker(74) *Attorney, Agent, or Firm*—Laura L. Whitmer(57) **CLAIM**

The ornamental design for a “substrate with printed pattern,” as shown and described.

DESCRIPTION

The sole FIGURE is a top view of an embodiment of a substrate with printed pattern showing our new design.

The dashed lines are for illustrative purposes only and form no part of the claimed design. The shading shown in the Figure represents the print pattern.
